UNITED STATES PATENT OFFICE

114,523

DESIGN FOR A TEXTILE FABRIC OR SIMILAR ARTICLE

Stanley Singer, New York, N. Y.

Application March 17, 1939, Serial No. 83,644

Term of patent 3½ years

To all whom it may concern:

Be it known that I, Stanley Singer, a citizen of the United States, residing at 780 Grand Concourse, in the county of Bronx, city of New York, and State of New York, have invented a new, original, and ornamental Design for a Textile Fabric or Similar Article, of which the following is a specification, reference being had to the accompanying drawing, forming part thereof.

The figure of the drawing is a plan view of a textile fabric showing my design.

The characteristic features of my design re-

side in the configuration shown, providing parallel rows of uniformly positioned triangles symmetrically arranged and defining uniform horizontal and vertical lines, all the triangular apices in any given row being similarly directed, while the apices in successive parallel rows are oppositely directed.

I claim:

The ornamental design for a textile fabric or similar article, as shown and described.

STANLEY SINGER.
